UNITED STATES PATENT OFFICE

HARRY W. TITGEN, OF GLENSIDE, PENNSYLVANIA

TUMBLING-MILL STRUCTURE

Application filed September 22, 1926. Serial No. 137,053.

My invention relates to tumbling mills, having particular relation to such mills as are applicable to the cleaning of rough castings and the like.

5 In its broad aspect, one object of my invention is to provide a continuously operating tumbling mill, wherein the materials under treatment as well as the cleaning elements are automatically fed through the 10 mill at a desired rate, and wherein the cleaning elements are automatically returned to the entrance end of the mill, so that the same cleaning elements may be continuously used so long as the mill is operated.

15 Another object of my invention is to provide a tumbling mill, wherein a feeding cone causes a movement of the articles under treatment and the cleaning means through an inlet passage of a shell into a principal 20 working chamber of the shell, the chamber being so formed that a further movement is imparted to the articles under treatment, causing the passage thereof from the working chamber into a discharge passage of the 25 shell.

A further object of my invention is to provide a tumbling mill, wherein a preliminary separation of undesirable materials from the articles under treatment is effected 30 in the inlet passage of the shell, the structure also effecting a further removal of such materials from the principal working chamber and the discharge passage leading therefrom.

35 With these and other objects and applications in mind, my invention further consists in the details of construction and operation and arrangement, hereinafter described and claimed and illustrated in the accompanying 40 drawings, wherein

Fig. 1 is a side elevational view of tumbling mill embodying my invention;

Fig. 2 is a horizontal sectional view of the structure of Fig. 1, with the hoppers for 45 the undesirable materials removed, the sectional plane being taken on the line II—II of Fig. 1;

Fig. 3 is an end elevational view of the structure of Fig. 1 looking from the right; 50 and

Fig. 4 is a transverse sectional view taken on the line IV—IV of Fig. 1.

Referring to the drawings, a tumbling mill 1 comprises an inner shell or drum 2 having front and rear end sections 3 and 4 providing inlet and outlet passages 5 and 6 and an intermediate section 7 defining a principal working chamber 8. The front end section 3 has an inlet opening 9 through which the articles under treatment, say, radiator castings, may be inserted and an outlet opening 11 connected to the working chamber 8. Similarly, the rear end section 4 is provided with an inlet opening 12 for the castings passing from the working chamber 8 and a discharge opening 13 for the cleaned castings.

In my co-pending application, Serial No. 90,577, filed Feb. 25, 1926, the sections 3, 4 and 7, together define a single cone. For 70 some classes of work, such construction was found undesirable inasmuch as the feeding action was too rapid. Frequently, it would be necessary to pass the castings through the conical shell a number of times in order 75 to obtain the desired cleaning action.

As a result of considerable experimental development, I have found that such undesirable results may be obviated by a construction as shown in Fig. 1 wherein the 80 front and rear sections 3 and 4 are of substantially cylindrical form and the intermediate section 7 is of enlarged cross-sectional area. The force necessary to cause the automatic feeding of the castings and 85 cleaning means, say, jacks, from the working chamber 8 through the discharge passage 6 is established by a front conical portion 14 of the intermediate section 7. The portion 14 extends from the outlet opening 11 of the front section 3 rearwardly to a 90 cylindrical portion 15. The extent of the feeding action by the conical portion 14 may be controlled by an oppositely tapered portion 16 which extends forwardly from the inlet opening 12 of the rear end section 4 to the cylindrical portion 15. It will be 95 noted that the angle of the tapered portion 16 is less than that of the portion 14, otherwise the castings and jacks would not leave 100

the cleaning chamber 8. The angular relation of these tapered portions is dependent upon the class of work under treatment.

Where it is desirable to vary the force imparted to the castings in the working chamber 8 after the construction of the drum 2, a conical shell 17 may be removably positioned in said working chamber with a smaller opening 18 thereof contiguous with the outlet opening 11 of the front end section 3 and with a larger opening 19 directly connected to the chamber formed by the cylindrical portion 15 of the working chamber 8. If necessary, the relative forces may be further varied by extending the tapered shell 17 to the oppositely tapered retarding portion 16, as shown by the dot-and-dash lines in Fig. 2.

Should the movement imparted to the castings and jacks in the working chamber 8 be insufficient to cause a corresponding movement of the castings in the outlet passage 12, a feeding cone 21 may be removably inserted, as shown in Fig. 2 wherein a smaller opening 22 thereof is substantially contiguous with the inlet opening 9 and a larger outlet opening 23 is substantially continuous with the passage 5. The cone 21 preferably extends to a rear portion 24 of the front section 3. The portion 24 has at least three openings 25 through which the jacks may be inserted into the inlet passage 5, all as will appear hereinafter in greater detail.

The castings inserted in the drum 2 through the inlet openings 9 or 22 generally having adhering thereto loose undesirable materials which should be separated therefrom before the castings pass into the principal working chamber 8. To this end, a portion 26 of the front end section 3 intermediate the apertured portion 24 and a front end portion 27 is provided with a plurality of openings through which said undesirable materials may pass. In the event that the feeding cone 21 is employed, a similar perforated portion 28 is provided therein which is positioned in alignment with the perforated portion 26.

The scale and other materials removed from the castings in the chamber 8 should be discharged at this point, otherwise said undesirable materials may be ground into the castings or the latter scratched thereby. Accordingly, the cylindrical portion 15 intermediate the oppositely tapered propelling and retarding portions 14 and 16 is provided with a plurality of discharge openings. Should the cone 17 be employed, this also is apertured.

The rear end section 4 comprises contiguous perforated portions 29, 31 and 32. The perforations of the portion 29 are relatively fine, so that only the smallest of the jacks as well as the undesirable materials carried by

the castings from the working chamber 8 may be discharged from the passage 6. The perforations of the portion 31 are of increased size, so that the jacks of average size may readily pass therethrough, while the perforations of the portion 32 are still larger, being shown in the form of slots, so that the jacks may readily pass therethrough rather than through the outlet opening 13 of the passage 6. The cleaning elements are thus gradually removed from the rear end section 4 as they approach the discharge outlet 13 thereof, only the larger of the cleaning elements reaching the end portion 32.

A plurality of longitudinally extending strips 33 may be mounted on the inner side of the drum 2, so that the castings as well as the jacks may be lifted upon a movement of said drum. The removal of undesirable materials, such, for example, as sand is thus further assured.

In order that the inlet passage 5 may be continuously supplied with jacks so long as the tumbling mill is in operation, I provide an outer conveyor shell or drum 34, the respective ends 35 and 36 of which surround the perforated portions 29, 31 and 32 of the rear end section 4 through which the jacks pass from the drum 2 and the apertured portion 24 through which the jacks enter the front end section 3 of the drum 2. The ends 35 and 36 of the conveyor shell 34 may be rigidly secured to the adjacent portions of the inner shell 2 by means of annular plates 37 and 38. These plates also serve to close the ends of an annular chamber 39 formed between the inner and outer shells 2 and 34.

The movement of the jacks immediately on entering the conveyor shell 34 may be facilitated by tapering a rear section 41 thereof oppositely to the tapered propelling portion 14 of the inner shell 2. The further movement of the jacks to the inlet openings 25 of the inner shell 2 may be effected by means of spiral flails 42 which may be mounted on the inner walls of the outer conveyor shell 34. The portions of the flails 42 adjacent to the apertured portion 24 are provided with enlarged sections 43, whereby the jacks may be lifted as the conveyor shell 34 rotates and permitted to fall under the action of gravity through the openings 25.

In order to prevent the jacks entering the passage 5 through an upper opening from escaping directly through a lower opening, shields 44 are provided. As shown in Figs. 2 and 4, these shields comprise an upwardly angled portion 45 spaced from the opening 25 and an end portion 46 which serves to prevent the castings from catching under the raised portion 45 during the movement toward the working chamber 8. The lifting of the jacks may be further facilitated by means of a plurality of lifting flights 47, of which three are shown in Fig. 4.

The materials removed from the castings in the principal working chamber 8 as well as in the discharge passage 6 passes into the conveyor shell 34. This material may be removed from the conveyor shell 34 by providing an intermediate portion 48 thereof with discharge openings 49. The portion 48 is preferably positioned in alignment with the perforated portion 15 of the working chamber 8. In order that such materials may be separated from the jacks while the whole is in a relatively loose condition, it will be noted that the flights 42 are extended over a part only of the perforated portion 48.

The perforated portion 48 of the outer conveyor shell 34 may be enclosed by a housing 51, as shown in Fig. 1, an upper portion 52 of which is provided with an outlet 53 leading to a suction fan (not shown), whereby the dust incident to the abrasive or cleaning operation may be removed. The heavier portions of the materials removed from the castings pass to hopper portions 54 of the housing 51.

The outer conveyor shell 34 is provided with an extension 55 having an apertured portion 56 positioned in alignment with the apertured portions 26 and 28 of the front end section 3 and the feeding cone 21, respectively. These apertured portions are enclosed by a housing 57 adapted to perform the same functions as the housing 51 for the perforated section 48. The open end of the extension 55 may be closed by an annular plate 58 which is so positioned on the front end section 3 of the inner shell 2 that the front end portion 27 extends outwardly beyond said plate 58.

The outer conveyor shell 34 is provided with a pair of spaced tires 59 and 61 which are respectively mounted on pairs of anti-friction supporting structures 62 and 63. Each of the structures 62, 63 comprises a pair of anti-friction rollers 64 and 65 which are mounted on a saddle 66 supported by a pivot pin 67 and a base structure 68. The weight carried by the rollers 64 and 65 may be adjusted by means of a screw member 69 which abuts against a shoulder 71 formed on the saddle 66. The rotation of the tumbling mill 1 may be effected by means of a driving motor 72 connected by gearing 73 to a pinion 74 meshing with a gear-wheel 75 rigidly secured to the outer conveyor shell 34.

Assuming the tumbling mill 1 in operation and a constant supply of jacks to the inlet passage 5, when the castings or other articles to be treated are inserted in the inlet passage 5 through the inlet opening 22 of the feeding cone 21, a force is imparted to said articles tending to feed the same in the direction of the principal working chamber 8. As the articles pass the perforated portions 26 and 28, a preliminary

removal of undesirable materials from the articles occurs. As the articles and the jacks or other cleaning elements enter the working chamber 8, an additional force is imparted to the same by the tapered portion 14, or by the cone 17 should this be employed instead. The movement of the articles and the cleaning elements out of the chamber 8, however, is retarded by the oppositely tapered portion 16 with the result that said articles are retained in the working chamber 8 a sufficient period to insure a thorough cleaning of the same. The undesirable materials formed as a result of the abrasive action in the chamber 8 are discharged through the perforated portion 15 thereof into the conveyor shell 34 and then through the apertures 49 in the outer shell portion 48 into the housing 51.

During the movement of the articles and the cleaning elements in the outlet passage 6, the removal of the undesirable materials from the articles is completed. The cleaning elements are also discharged through the apertured portions 29, 31 and 32, and the finished articles finally passed through the outlet opening 13. The cleaning elements discharged from the passage 6 are conveyed by the tapered portion 41 of the conveyor shell 34 to the flails 42. The latter in combination with the flights 47 then cause a further movement of the cleaning elements through the inlet openings 25. The shell 34 thus provides a return path for the cleaning elements and insures a constant supply of the same in the inlet passage 5 so long as the tumbling mill is in operation.

While I have shown only one form of embodiment of my invention, for the purpose of describing the same and illustrating its principles of construction and operation, it is apparent that various changes and modifications may be made therein without departing from the spirit of my invention, and I desire, therefore, that only such limitations shall be imposed thereon as are indicated in the appended claims or as are demanded by the prior art.

I claim:

1. A tumbling barrel shell provided with a principal working chamber and inlet and outlet passages for said chamber, said inlet passage having openings through which undesirable materials may be removed, and cleaning elements inserted, respectively, said outlet passage having openings through which the cleaning elements may be discharged and means for receiving the cleaning elements at an outlet passage and for returning them to said openings in the inlet passage.

2. A tumbling barrel drum having one section formed to constitute a principal working chamber and connected sections defining inlet and outlet passages, said inlet

- passage having one set of openings permitting a preliminary separation of undesirable materials from the articles under treatment and another set of openings through which cleaning elements may enter, said outlet passage having openings through which said cleaning elements may be discharged, said working chamber also having openings permitting the removal of undesirable materials.
3. A tumbling barrel shell having a principal working chamber and inlet and outlet passages therefor, said chamber being so formed that the articles under treatment will be fed through said shell in a substantially continuous stream, but so that they may be retained therein a desired interval, said inlet passage having one set of openings permitting a preliminary removal of undesirable materials and a second set of openings through which the cleaning elements may be passed, said principal working chamber having openings through which undesirable materials may be discharged, and said outlet passage having openings permitting the discharge of said cleaning means as well as undesirable materials and means for returning said cleaning means from said outlet passage to the second set of openings in said inlet passage.
4. A tumbling mill comprising a drum having inlet and discharge openings for the articles to be treated and the cleaning elements, at least one portion of said drum being formed to impart a movement to said cleaning elements axially of said drum, means whereby said movement may be retarded to a desired extent, and a second drum interconnecting certain of said openings so as to provide a return path for the cleaning elements.
5. A tumbling mill comprising a drum having entrance and discharge openings for the articles under treatment, means adjacent to said entrance opening for guiding said articles into said drum and for causing a preliminary separation of the undesirable materials from said articles, means adjacent to said discharge opening for guiding said articles from said drum and for discharging the cleaning means therefrom, one section of said drum defining a working chamber formed to cause a movement of said articles therefrom, means whereby undesirable materials may be removed from said working chamber, and means connected to said first and second-mentioned means in said drum so that the cleaning means discharged from said drum may be conveyed to another portion thereof immediately connected with the entrance end of said working chamber.
6. A tumbling barrel drum provided with a working chamber and inlet and outlet passages, said inlet passage being formed to cause feeding of the articles under treat-

ment and the cleaning means to said chamber, the latter being formed to cause feeding of said articles and cleaning means through said chamber, means arranged substantially concentrically with said drum for returning to said inlet passage the cleaning means discharged from said drum, and means whereby undesirable materials may be removed from said inlet passage.

7. A tumbling barrel drum provided with a principal working chamber and inlet and outlet passages, said inlet passage being formed to cause feeding of the articles under treatment and the cleaning means to said chamber, the latter having oppositely tapered portions adapted to cause feeding of said articles and cleaning means from said chamber, means arranged substantially concentrically with said drum for returning to said inlet passage the cleaning means discharged from said drum, so that the same cleaning means may be continuously used, and means whereby undesirable materials may be removed from said inlet passage.

8. A tumbling mill comprising a drum having entrance and discharge openings, said drum being provided with openings adjacent to said entrance opening through which cleaning means may be inserted and undesirable materials may be discharged, said shell also having discharge openings for said cleaning means adjacent to said drum discharge opening, and a conveyor drum interconnecting the discharge and inlet openings for said cleaning means.

9. A tumbling mill comprising a drum having inlet and outlet ends, said drum having openings adjacent to said inlet end through which the cleaning means may be inserted and undesirable materials discharged, said drum having discharge openings for the cleaning means adjacent to said outlet end, a conveyor shell for interconnecting the discharge and inlet openings for said cleaning means, and means whereby undesirable material passing into said conveyor drum may be removed.

10. A tumbling mill comprising an inner shell provided with openings adjacent to one end for the insertion of the cleaning means and the discharge of undesirable materials, said shell having at least one opening adjacent to the other end for the discharge of the cleaning means, an intermediate section of said shell being of enlarged cross-sectional area so as to cause the articles under treatment to be retained therein a desired time interval, and an outer conveyor shell having a tapered portion adapted to receive the cleaning means passing through said last-mentioned opening, another portion being in operative relation to the inlet opening for the cleaning means.

11. A tumbling barrel comprising a drum having inlet and outlet ends, an intermediate

section of said drum having spaced oppositely tapered portions defining a working chamber, said drum having inlet and outlet openings for the cleaning means adjacent to said ends, and a conveyor shell for interconnecting said openings, so that the same cleaning means may be continuously used.

12. A tumbling mill comprising a shell having cylindrical end sections and an enlarged intermediate section defining a working chamber, one section having openings through which the cleaning means may be inserted and undesirable materials removed, the other end section having discharge openings for the cleaning means, and a conveyor shell connecting the inlet and discharge openings for the cleaning means, so that a continuous supply of cleaning means may be assured for said working chamber.

13. A tumbling mill comprising a shell having cylindrical end sections and an enlarged intermediate section, one end section having inlet and discharge openings for the cleaning means and the undesirable materials, the other end section having discharge openings for the cleaning means, a conveyor shell interconnecting said inlet and discharge openings for the cleaning means and also adapted to receive the undesirable materials discharged from said intermediate section, said conveyor shell having openings through which said last-mentioned materials may be discharged and also provided with an extension adapted to receive the undesirable material from said first-mentioned discharge openings, said extension also having discharge openings.

14. A tumbling barrel shell having cylindrical end sections and an intermediate section of enlarged diameter formed to cause an automatic feeding therethrough of the articles under treatment, one end section having openings for the insertion of the cleaning means and the discharge of undesirable materials and also provided with a feeding cone, the other end section having discharge openings for the cleaning means, a conveyor shell interconnecting the inlet and discharge openings for said cleaning means, said conveyor shell being provided with an extension adapted to receive said first-mentioned undesirable material.

HARRY W. TITGEN.
